UNITED STATES PATENT OFFICE

2,491,326

BAND PASS AMPLIFIER

William W. Moe, Stratford, Conn., assignor to
 General Electric Company, a corporation of
 New York

Application May 26, 1945; Serial No. 595,915

4 Claims. (Cl. 179—171)

1

My invention relates to interstage coupling circuits for amplifiers and it has for one of its objects to provide a certain improvement therein whereby greater transmission gain is had without complication of the circuits.

A further object of the invention is to provide such a coupling circuit having the advantage that its frequency of resonance is less affected by variations in unidirectional potential applied between the grid and cathode of the second stage, as for automatic volume control purposes.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents an embodiment of my invention and Fig. 2 represents a modification thereof.

Referring to Fig. 1, I have indicated at 1 and 2 a first and second electron discharge amplifier, the amplifier 1 having an anode and cathode between which an operating voltage is supplied through a resistance 3. This source of operating voltage may be connected between the cathodes of the two amplifiers, which may be grounded, and the conductor 4 and may be bypassed for frequencies at which the amplifier operates by means of condenser 5. The anode of discharge device 1 is coupled for currents of the frequency to be amplified to the input of amplifier 2 by means of the coupling and blocking capacity 6 and inductance coil 7, the grid of the amplifier 2 being connected to the tap 8 on the coil 7.

It has been found that very important advantages are obtained by connecting the grid of the device 2 to the tap 8 on the inductance coil rather than to the upper terminal thereof and by the proper positioning of the tap 8 on the coil 7. The position of this tap should be such that the capacity between the grid and cathode of the device 2 is reflected by the coil 7 as a smaller capacity between the anode and cathode of device 1, this smaller capacity being substantially equal to the interelectrode capacity between the anode and all other electrodes of the device 1. These two capacities are indicated by dotted lines 9 and form the capacity which resonates with the inductance of the coil 7. The capacity 6 is, of course, a large capacity which does not materially influence the frequency of resonance.

If the electron discharge devices employed be of

the 6AC7 type, having a control electrode and screen and suppressor electrodes, the interelectrode capacity between the anode and all other elements of device 1 may be of the order of five micromicrofarads whereas the interelectrode capacity between the grid and all other elements of device 2 may be 15 micromicrofarads. The position of the tap 8 should then be such that the impedance of the whole coil 7 has the same ratio to the impedance of the coil between the tap 8 and ground that the capacity between the grid and all other elements of device 2 has to the capacity between the anode and all other elements of device 1. The 15 $\mu\mu$ f. of capacity between the grid and other elements is then reflected as 5 $\mu\mu$ f. across the entire coil 7. This 5 $\mu\mu$ f. is then added to the 5 $\mu\mu$ f. of anode capacity of device 1 to produce the equivalent of 10 $\mu\mu$ f. of capacity across the entire coil 7. Resistance 3 may then be given a value to adjust the circuit to the bandwidth which it is desired to transmit. When the amplifier is used as an intermediate frequency amplifier in a television receiver, for example, or as an intermediate frequency amplifier of a pulsed carrier wave receiver the bandwidth to be transmitted may extend, for example, from 28 to 32 megacycles.

It has been found that for the same bandwidths and same Q of the tuned circuit comprising capacity 9 and inductance 7 the resistance 3 may be substantially double the value which would obtain if the tap 8 were moved to the upper extremity of the coil 7.

The advantage in employing the tap 8 can best be understood by considering the circuit if the tap 8 be moved to the upper extremity of the coil. Let us assume that sufficient input voltage is then applied to the grid of tube 1 to produce one volt between the anode and cathode of tube 1. Since the capacity of condenser 6 is large, this one volt is then applied directly between the grid and cathode of the device 2. The 15 $\mu\mu$ f. input capacity between the grid and other elements of the device 2 plus the 5 $\mu\mu$ f. output capacity between the anode and other elements of device 2 then add to 20 $\mu\mu$ f. which resonates with the inductance of the coil 7 at the operating frequency. The resistance 3 is then given a value to produce the required Q or transmission bandwidth of the circuit.

Assuming now that the tap 8 be adjusted to a position such that the input capacity of device 2 is reflected across the entire coil 7 with a value equal to the output capacity of device 1, or 5 $\mu\mu$ f. Coil 7 may then be adjusted for resonance at the

same frequency with this smaller total capacity, 10 μ uf., which is only half of the capacity with which it previously resonated. Resistance 3 may now be doubled to produce the same transmission bandwidth with the result that the same voltage applied between the grid and cathode of device 1 produces two volts between the anode and cathode of device 1. Now since the ratio of the impedance of the entire coil 7 to the impedance between the tap 8 and ground is 3 to 1, this voltage is stepped down by a ratio of 1.73 to 1 and the voltage applied between the grid and cathode is the quotient of 2/1.73 or 1.16. Thus a 16% increase in gain per stage is produced by reason of the stepdown position of the tap 8. Thus by using the coil 7 as a stepdown autotransformer of the proper ratio, an increase in voltage amplification is obtained in the amplifier.

In multistage amplifiers such as may be used in pulse receivers this is very important. Thus in an eight-stage amplifier a gain of 16% in each stage increases the total gain of all of the amplifiers by a ratio of 3.3 to 1.

The use of the autotransformer 7 with the step-down connection is also of particular importance where variable direct current voltage is applied between the grid and the cathode of the device 2 as for gain control purposes, for example. This connection is shown in Fig. 2 where the lower terminal of the coil 7 is shown connected to ground through the by-pass condenser 10, and to a conductor 11 on which variable unidirectional voltage with respect to the cathode is applied for gain control purposes. This variable control voltage, of course, varies to some extent the capacity between the grid and cathode of the device 2 but since this capacity as reflected across the entire coil 7 is reduced to one-third, variations therein are correspondingly reduced and thus effect to a considerably smaller extent the frequency to which the circuit is resonant. With the proportions mentioned, these variations are reduced by about 50%.

While I have shown a particular embodiment of my invention it will, of course, be understood that I do not wish to be limited thereto since different modifications may be made and I contemplate by the appended claims to cover any such modifications as fall within the true spirit and scope of my invention.

What I claim as new and desire to secure by Letters Patent of the United States, is:

1. An amplifier comprising a first electron discharge device having an anode and cathode, a second discharge device having a grid and cathode, an inductance coil connected between said anode and cathode, a portion of said inductance coil being connected between said grid and cathode, the impedance of said coil having the same ratio to the impedance of said portion that the capacity between said grid and cathode has to the capacity between said anode and cathode.

2. In combination, a first electron discharge device having an anode and a cathode, a second electron discharge device having a grid and a cathode, a coupling between the anode and cathode of said first device and the grid and cathode of said second device comprising an inductance coil connected between said anode and cathode, a portion of said inductance coil being connected between said grid and cathode, the impedance of said coil having the same ratio to the im-

pedance of said portion that the capacity between said grid and cathode has to the capacity between said anode and cathode, and said inductance coil being resonant with said capacities at the operating frequency of said amplifier, said capacities and the distributed capacities of said coil and circuits connected thereto comprising the sole capacity resonating said coil, and a resistance across said coil proportioned in accord with the frequency bandwidth transmitted by said coupling.

3. In an amplifier comprising a first stage having an anode and cathode and a second stage having a grid and cathode, said cathodes being connected together, and an inductance coil connected between said anode and cathode the voltage on which is supplied between said grid and cathode, the combination of means to increase said voltage comprising a tap from said grid to a point on said coil so positioned that the impedance of said coil to the impedance between said tap and said cathodes has the same relation that the capacity between said grid and cathode has to the capacity between said anode and cathode, said coil being resonant with said capacities at the frequency which said amplifier operates, and a resistance connected across said coil having a value to produce desired bandwidth of oscillations transmitted between said amplifier and greater than the value required to produce the same bandwidth were the whole of said coil connected between said grid and cathode.

4. The combination, in an amplifier comprising a first stage having an anode and cathode and a second stage having a grid and cathode, the capacity between said grid and cathode being greater than that between said anode and cathode, a source of operating potential connected between said anode and cathode through a resistance, a capacitance and an inductance coil connected in series between said anode and cathode, said grid being connected to an intermediate point on said inductance so positioned that the inductance of said coil has the same ratio to the inductance between said intermediate point and cathode as the capacity between said grid and cathode has to the capacity between said anode and cathode, whereby the capacity between said grid and cathode is reflected as a smaller capacity between said anode and cathode and is added to the interelectrode capacity between said anode and cathode, said inductance being proportioned to resonate with the total capacity between said anode and cathode at the operating frequency, and means to supply a variable unidirectional voltage between said grid and cathode to vary the amplification of said second stage whereby the variation in frequency to which said coil is resonant produced by variation in said unidirectional voltage is reduced due to reflection by said coil of said grid to cathode capacity as a smaller capacity between said anode and cathode.
